UNITED STATES PATENT OFFICE

LEWIS WEST, OF MONETT, MISSOURI.

WASHBOILER.

1,029,778.

Specification of Letters Patent. Patented June 18, 1912.

Application filed October 7, 1910. Serial No. 585,844.

To all whom it may concern:

Be it known that I, LEWIS WEST, a citizen of the United States, residing at Monett, in the county of Barry and State of Missouri, have invented certain new and useful Improvements in Washboilers, of which the following is a specification.

This invention relates to improvements in wash boilers and similar devices, and has for 10 one of its objects to improve the construction and increase the efficiency and utility of devices of this character.

Another object of the invention is to provide a device of this character wherein provision is made for supporting the garments spaced from the bottom of the boiler and likewise for draining the garments after the boiling operation before they are removed from the boiler.

20 Another object of the invention is to provide a device of this character having a draining appliance and with means for suspending the appliance within the boiler and spaced below the top.

25 Another object of the invention is to provide a device of this character having a cover supported within the boiler and a short distance below the rim so that all danger of the water boiling over is effectually prevented.

30 Another object of the invention is to provide a device of this character having a cover supported below the top of the rim to prevent the water from boiling over, and 35 adapted to be locked from upward movement so that the pressure produced by the boiling of the water and the expansion of the garments will not result in displacing the cover.

40 With these and other objects in view the invention consists in certain novel features of construction as hereinafter shown and described and then specifically pointed out in the claim; and, the drawings illustrative 45 of the preferred embodiment of the invention.

Figure 1 is a longitudinal sectional view of the improved device. Fig. 2 is a plan view of the drainer member. Fig. 3 is a 50 transverse section on the line 2—2 of Fig. 1. Fig. 4 is a transverse section showing the drainage member in its upward position, or in position to drain the garments. Fig. 5 is a perspective view of one of the cover 55 locking devices.

The boiler portion of the improved de-

vice is represented conventionally at 10 and provided with the usual outwardly directed rolled rim at 11. The boiler may be of any required size and any suitable material, but 60 will generally be the ordinary form and of the ordinary material, as the improved attachments do not require any change whatever in the boiler, and may be adapted without material structural changes to different 65 forms and sizes of boilers. Located within the boiler is a perforated drainage member 12 having a concave under face and a convex upper face. Located upon the upper face of the member 12 are a plurality of concentrically arranged ribs 13 which serve to support the garments above the body of the drainage member, and to this end any number of these ribs may be employed and spaced any required distance. Generally two of the ribs 70 75 will be sufficient, but it will be understood that it is not desired to limit the number of the ribs in any manner or to any distance between them. In practice strips which are L-shaped transversely are employed as 80 shown.

The perforations indicated at 14 are preferably so spaced that they come between the ribs, with none of the perforations covered by the ribs. Wash boilers are generally constructed with flat sides and rounded ends, and the drainage member 12 conforms to the outlines of the boiler, but it will be understood that the drainage member will be formed to correspond to the outlines of the 85 90 boiler whatever form the latter may possess. Rising from the member 12 are a plurality of brackets 15, preferably two at each side, and with sockets in their upper ends to receive the rods 16. Mounted to swing upon 95 the rods 16, preferably outside of the brackets 15 are bails 17, each bail having eyes 18 at its terminals for engaging around the rods 16 and with offsets 19 next to the eyes. By this arrangement when the drainage 100 member 12 is located in the bottom of the boiler, as shown in Figs. 3 and 4 the bails will bear at their upper bight ends against the sides of the boiler with the space between them for the garments. After the boiling 105 operation the bails are utilized to elevate the drainage member 12 together with the garments, the bails then swung in opposite directions upon the rods as hinges and the offsets 19 of the bails bearing upon the upper rim of the boiler and the bodies of the bails directed downwardly alongside of the 110

boiler, as shown in Fig. 4. By this means the bails are utilized to hold the drainage member in its upward position, and after the drainage is completed the bails may 5 again be employed to lift the drainage member together with the garments thereon bodily from the boiler.

It will thus be noted that a simply constructed and convenient device is produced 10 whereby the clothes are supported away from the bottom of the boiler by the upwardly directed drainage member, and then supported in position until the drainage is completed and then removed from the boiler, 15 the drainage member thus performing three distinct and separate functions. A cover to the boiler also forms a part of the improved device and is represented conventionally at 20 and is convex upon the upper 20 face and concave on the lower face, and will conform substantially to the shape of the boiler, but will be slightly smaller than the boiler so that water can pass freely between the closure and the sides of the boiler. At its 25 ends the cover 20 is provided with hooks 21 for bearing over the rim 11 of the boiler, and thus supporting the cover in position. Rising from the sides of the cover 20 are loops 22, and swinging upon these loops are hooks 30 23, preferably formed of sheet metal and with inwardly directed tongues 24 for engaging beneath the outwardly turned roll or rim 11 of the boiler when the cover 20 is in position, and thus effectually lock the 35 cover from upward movement. This is an important advantage in devices of this character, as the upward pressure created by the boiling water and the swelling of the garments is considerable and frequently results 40 in displacing the cover. This would be especially true in a construction such as shown in this application with the cover located a short distance below the top of the boiler,

whereby the upward pressure against the cover is greater. Preferably, the cover 20 45 is formed with any desired number of perforations, as best illustrated in Fig. 1.

The improved device is simple in construction, can be inexpensively manufactured, and can be applied without material 50 structural changes to different forms of boilers and without requiring any change whatever in the boiler.

By this means if the boiler is required for other purposes than boiling clothes the attachments may be readily removed, as will be obvious.

Having thus described my invention, what is claimed as new is.

The combination with a wash boiler having an outwardly projecting rim, of a cover removably fitted within the boiler and lying in a plane below the said rim, and means for supporting the cover and for holding it against upward displacement, said means comprising loops secured upon the cover at opposite sides thereof and keepers pivotally connected one with each of the loops, each of the keepers comprising a plate bent to form a right angularly projecting flange 70 having an extension bent to form a pivot lug connected with the respective loop, the said flange being arranged to project over the said rim with the body of the plate extending down beside the rim exterior to the 75 boiler, and the said plate having a lug stamped to project at an angle from the inner side thereof and engaging beneath the said rim.

In testimony whereof, I affix my signature 80 in presence of two witnesses.

LEWIS WEST. [L. S.]
